UNITED STATES PATENT OFFICE.

CLEMENT C. CLAWSON, OF NEWARK, NEW JERSEY.

COIN-CONTROLLED AIR-PUMP-OPERATING MECHANISM.

SPECIFICATION forming part of Letters Patent No. 619,279, dated February 14, 1899.

Application filed June 30, 1898. Serial No. 684,779. (No model.)

To all whom it may concern:

Be it known that I, CLEMENT C. CLAWSON, a citizen of the United States, residing at Newark, in the county of Essex and State of New Jersey, have invented certain new and useful Improvements in Coin-Controlled Air-Pump-Operating Mechanism; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The present invention has reference to a novel construction of coin-controlled mechanism in which by the depositing of a coin a pump-operating mechanism becomes freed and can be worked by the turning of a crank.

The object of my invention, therefore, is to provide a novel construction of apparatus of this character in which after the mechanism has been freed by a deposited coin one or more air-forcing pumps can be operated to drive or force the air through a pipe or tube connected with the casing of the apparatus and from which the air can be forced to inflate the object connected with or attached to the end of the said tube.

One of the principal objects of my present invention is to provide a machine or apparatus which can be secured to the side of a building or post to enable riders of bicycles to inflate the tires of their vehicles along the road by simply dropping a coin into the slot of the apparatus, attaching the air-inflating tube connected with the apparatus to the tire of the wheel of the bicycle, and by turning the crank of the apparatus forcing air into the tire to fully inflate the same.

A further object of my invention is to provide an apparatus or machine of the nature and for the purposes stated which shall be of a compact, reliable, and efficient construction.

The invention therefore consists in the novel construction of coin-controlled mechanism and means for driving or operating an air pump or pumps; and the invention, furthermore, consists in the novel features of construction and the several arrangements and combinations of the parts of such mechanism, all of which will be fully described in the ac-

companying specification and finally embodied in the clauses of the claim thereto appended.

The invention is clearly illustrated in the accompanying drawings, in which—

Figure 1 is a front view of my novel construction of apparatus, and Fig. 2 is a top view of the same. Fig. 3 is a front view of the apparatus with a pair of doors in the front of the casing removed to illustrate one arrangement of the controlled mechanism within the casing, the several parts being represented in their normally inoperative positions; and Fig. 4 is a horizontal section of the casing, taken on line 4 4 in said Fig. 3, said view illustrating in top view the general arrangement of the operating mechanism embodying the principles of this invention. Fig. 5 is a longitudinal vertical section of the casing with the pump-operating mechanism represented in front elevation, the coin-controlled mechanism being represented in its freed position to permit the actuation of the pump-operating mechanism. Fig. 6 is a horizontal section of the several parts, said section being taken on line 6 6 in said Fig. 3. Fig. 7 is a longitudinal vertical section of the casing and a front elevation of one arrangement of three air-pumps, a three-way valve and connecting-tubing, and a means for operating said pumps; and Fig. 8 is a horizontal section taken on line 8 8 in said Fig. 3. Fig. 9 is a vertical cross-section taken on line 9 9 in Fig. 5, illustrating a portion of the coin-chute in cross-section and the operating mechanism directly connected therewith being presented in end elevation, but the arrangement of air-pumps being omitted in this view. Figs. 10 and 11 are a face and edge view, respectively, of a cam and a portion of the operating-shaft on which it is arranged for working the air pump or pumps. Fig. 12 is a longitudinal vertical section of one of the air-pumps. Fig. 13 is a horizontal section of the same, taken on line 13 13 in said Fig. 12; and Fig. 14 is a similar section taken on line 14 14 in said Fig. 12 when looking in the direction of the arrow x in said figure. Fig. 15 is a side view of a guide-frame and rollers employed in connection with the air-pump. Fig. 16 is a longitudinal vertical section of said guide-frame, and Fig. 17 is a plan view or top view of said

frame. Figs. 18 and 19 are detail views of a pair of receivers or holders adapted to embrace and retain the air-pump in proper position in the casing of the apparatus, and Figs. 20 and 21 are the respective end views of the devices illustrated in said Figs. 18 and 19.

Similar letters of reference are employed in all of the above-described views to indicate corresponding parts.

- 10 In the said drawings, A designates a suitable casing of iron or wood, which is preferably of the shape indicated in the several figures of the drawings, being provided with a back a , sides a' , and top and bottom sides a^2 .
- 15 In the said back a there is a suitable arrangement of holes, as a^4 , for the reception of screws or nails, whereby the device can be securely attached to the side of a building or post, as will be clearly evident.
- 20 The sides and the top and bottom pieces of the casing A are preferably provided with a suitable and ornamental molding a^5 , and a cross piece or bar a^6 connects the two sides a' of the casing A in such a manner that an opening a^7 will be formed at the top and an opening a^8 will be formed in the lower portion of the front of the casing, as will be clearly seen from an inspection of Fig. 3. Said openings a^7 and a^8 are formed on three of their 25 marginal edges with flanges a^9 , on which can be made to rest the doors b and b' , as indicated in Figs. 1, 4, 8, and 9. Each door b and b' has a flange or lip b^2 , which fits under the edge a^{10} of each opening a^7 and a^8 , and in the 30 door b is the usual form of coin-slot b^3 and a lock b^4 , while the door b' is provided with a lock b^5 , whereby, as will be clearly evident, the said doors can be securely held in their locked positions in the said openings a^7 and a^8 35 of the casing A to protect the mechanism within the said casing.
- 40

In suitable bearing portions in the cross piece or bar a^6 and in the back a of the casing A is rotatively arranged a main shaft c , which projects from the front of the said piece or bar a^6 and has a crank c' secured thereon, as clearly indicated in Figs. 1, 2, and 4. On the said shaft c I have secured a peculiarly-constructed wheel d , which is provided with 45 a hub d' and a set-screw d^2 for firmly securing it upon the shaft c . Said wheel d has a web portion d^3 , from the inner side of which extends an annular or circular flange d^4 , which, however, is eccentrically placed in relation to the central longitudinal axis of the 50 wheel d . The said web d^3 has an opening d^5 in the one side thereof, which is for the purpose of reducing the weight of metal and to facilitate the getting at the set-screw d^2 in 55 securing the said wheel d in its operative position upon the shaft c ; but said opening d^5 is not essential and may be dispensed with, if desired. The periphery of the said wheel d is provided with a suitable arrangement of 60 ratchet-teeth d^6 , formed in the manner clearly illustrated in Figs. 3 and 5, and f is a suitable dog or pawl pivotally arranged on a pin 65

f' , extending from the back of the said cross piece or bar a^6 , and f^2 is a weighted arm on said dog or pawl to cause the part f^3 of said pawl to hang in constant sliding engagement with the peripheral surface of the said wheel d and against the ratchet-teeth thereon to permit of the forward rotary movement of said wheel, but to prevent any backward movement of said wheel by the said part f^3 coming in stopping engagement with the angular portion of the ratchet-teeth of the said wheel. At a suitable point in the upper right-hand portion of the periphery of said wheel d when the parts of the mechanism are in their normally inoperative positions there is a squared projection d^7 , which forms a suitable stop, for the purpose to be hereinafter more fully set forth. Directly back of said projection d^7 the said wheel is provided with a pair of inclined surfaces d^8 and d^9 , the same forming a $\wedge$ -shaped portion between the said projection d^7 and the following ratchet-tooth d^6 , as will be clearly seen from an inspection of said Figs. 3 and 5. Directly back of the said wheel d and secured upon the said shaft c by means of a set-screw g^2 between the hub d' of the wheel d and the inner surface of the back a of the casing A is the hub g' of a suitable cam-disk g , the purpose of which will be more fully set forth in connection with the description of the air pump or pumps. As will be seen more especially from an inspection of Fig. 8, the said back a of the casing is provided with a suitable post a^{11} , having a screw-threaded opening a^{12} . Rotatively secured on a pin or screw j , screwed into the said opening in the end of the post a^{11} , is a disk e , having a circular peripheral edge portion e' and an eccentrically-placed curved edge portion e^2 , a pair of diagonally-arranged portions e^3 and e^4 being provided to connect the said portions e' and e^2 in the manner illustrated more particularly in Figs. 3 and 5. Secured to the said disk e by means of screws e^5 or in any other well-known manner is a second disk e^6 , which is provided on its peripheral surface with suitable ratchet-teeth e^7 . On a suitable post or pin h is a hub h' , which is provided with a downwardly-extending arm h^3 , having a finger portion h^4 at its lower end projecting at a right angle therefrom and being normally in sliding engagement with the edge portions e' or e^2 of the disk e . Said arm h^3 has projecting from one edge thereof an arm h^5 , having a finger portion h^6 , formed at a right angle at the lower end thereof and extending directly beneath the discharge-opening of a suitable coin-chute i , as clearly indicated in Figs. 3, 5, 6, and 9. To prevent any backward movement of the two disks e and e^6 , I have pivoted to said arm h^5 a suitably-constructed dog or pawl h^7 , which slides over the ratchet-teeth of said disk e^6 when moving in the proper direction; but which prevents any backward movement thereof, as will be understood. Pivotally arranged upon the pin j , hereinabove mentioned,

is a rod or lever k , which is provided at its free end with a screw k' and a roller or wheel k^2 , arranged on said screw. Said rod or lever k is provided with a pin or post k^3 , and the 5 arm h^5 , hereinabove mentioned, has an eye or loop h^8 , the said loop or eye and the post k^3 being connected by a coiled spring m , substantially as illustrated in Fig. 3. The normal tendency of this spring m when the several 10 parts of the mechanism are in the positions indicated in said Fig. 3 is to force the end of the upwardly-extending arm h^2 directly against the stop portion of the projection d^7 of the wheel d , with the finger portion h^4 of 15 the arm h^5 in holding or locked engagement with the stop formed by the diagonal portion e^3 , connecting the peripheral edge portions e' and e^2 of the disk e . At the same time the finger portion h^6 of the arm h^5 is forced up directly 20 against the under surface of the discharge-opening in the coin-chute i , and a coin which has been dropped in the chute i will be retained therein, near the bottom, by resting on the said finger portion h^6 and against the 25 inner curved surface i' of the coin-passage within the chute, as indicated in said Fig. 3. Said spring m , connected with the arm or lever k , will also cause the constant operative rolling contact of the wheel or roller k^2 with 30 the eccentrically-arranged annular flange d^4 of the wheel d . As will be seen from Figs. 3 and 5, pivotally attached to the said rod or lever k is a suitable dog or pawl k^4 , having a tooth k^5 , which is forced in operative engagement 35 with the ratchet-teeth e^7 of the disk e^6 by the weighted end portion k^6 of said pawl. From the above description of these several parts and an inspection of said Fig. 3 it will be clearly evident that the mechanism is 40 locked and that the shaft c and parts connected therewith cannot possibly be operated until the mechanism is released in the manner to be described. The said coin-chute i consists, essentially, of a pair of peculiarly-bent plates i^2 and i^3 , said plate i^2 having suitably-spaced ribs i^4 , upon which the said plate i^3 is secured by means of screws i^5 to form the complete chute. Said plate i^2 also has a pair of brackets i^6 , whereby the chute 45 can be secured in position within the casing A against one of its sides a' , as indicated in the several figures of the drawings, with the inlet or mouth of the coin-chute directly back of the coin-slot in the door b and the outlet 50 of the said coin-chute i directly above the finger portion of the arm h^5 . As will be noticed from Figs. 3, 5, 6, and 9, the said plate i^2 is also provided with a perforated bearing portion i^7 , which extends directly over the 55 edge of the plate i^2 and above a slot i^8 in said plate. (See more particularly Fig. 9.) In this bearing portion i^7 and in a suitable perforation in the top a^2 of the casing A , I have arranged a rod n , provided on the outside of 60 said casing with an ornamental knob n' . The lower portion n^2 of said rod, as will be seen from said Fig. 9, extends below said bearing 65 i^7 and down into the said slot i^8 in the plate i^2 of the coin-chute, a portion of said rod extending into the coin-passage of the chute i . 70 Said rod is normally held above the coin which has been deposited in the chute by a spring n^3 , which encircles the said rod n on that portion located between the inner surface of the top of the casing A and said bearing i^7 75 in the manner illustrated in Figs. 3 and 5. Now as soon as a coin has been dropped into the said coin-chute i it will be retained in the position indicated in dotted outline in said Fig. 3. By applying a downward pressure 80 upon the knob n' of the rod n the end n^2 of said rod is brought down upon the edge of the coin. The latter will thus be caused to partially project from the discharge-opening in the chute i , thereby exerting a pressure 85 upon the finger portion h^6 of the arm h^5 , whereby the arm h^2 will be disengaged from the projection d^7 on the wheel d and the finger portion h^4 of the arm h^5 will be lifted away from the portion e^3 of the disk e , as 90 clearly illustrated in Fig. 5, with the coin still retained in the position indicated in said figure. The crank connected with the shaft c can now be operated to turn said shaft and all the parts connected therewith. In the 95 meantime the spring m causes the roller or wheel k^2 on the arm k to roll against the annular surface of the eccentric projection or flange d^4 of the wheel d , which with each revolution of the shaft c and the wheel d 100 causes a vibratory motion of the rod or lever k , and hence the latter by means of the dog or pawl k^4 produces an intermittent rotary motion of the disk e^6 and disk e on the pin j . As soon as the highest point of the eccentrically-placed curved edge portion e^2 engages 105 the finger portion h^4 of the arm h^5 said arm h^5 and the arms h^2 and h^5 will be moved slightly forward, owing to a partial rotation of the hub h' upon its pivotal post or pin h , 110 whereby the finger portion h^6 of the arm h^5 is brought farther away from the discharge-opening in the chute and the coin is permitted to finally drop down into the lower part of the casing A . As soon as the coin 115 has passed from the chute i the spring m causes the finger h^4 of the arm h^5 to rest in sliding contact on the circular edge e' of the disk e . The shaft c and parts thereon are thus still permitted to be operated, the said 120 circular flange d^4 on the wheel d being so arranged that one revolution of the flange and wheel will cause but a partial rotary motion of the disks e and e^6 equal to the distance between two consecutive ratchet-teeth on said 125 disk e^6 . These several parts of the mechanism are so arranged and timed that about fifteen complete revolutions of the shaft and wheel d will have caused but one complete revolution of the disks e and e^6 , and at the end 130 of this one revolution of said disks the finger portion h^4 of the arm h^5 will once more drop behind the straight part e^3 on the disk e and the end of the arm h^2 thereby brought in its

holding or locked engagement with the projection d^7 on the wheel d , with the several parts of mechanism in their normally inoperative positions and the finger portion h^6 of the arm h^5 directly beneath the discharge-opening of the coin-chute i , as indicated in said Fig. 3. The device is now ready for a second operation when another coin is deposited into the chute i .

10 I will now describe the manner of arranging and operating the air pump or pumps when the shaft c revolves in the manner just described.

In Figs. 7 and 8 I have illustrated one manner of arranging and securing the air-pumps in their operative positions to be worked by the cam-shaped disk g , which is connected with the shaft c , as above stated. Secured to the back a of the casing A , preferably upon 15 suitably disposed enlargements or projections, as a^{13} , (see Fig. 8,) is a receiver or holder section l , to which is secured a second receiver or holder section l' , the same being secured together in such a manner to form a 20 socket or receiving portion in which a pump o is securely and operatively held. Said section l is formed with a semicylindrical part l^2 and a connecting-wall l^3 . The outer portion of said part l^2 is made with angular sides 25 l^4 and has holes l^5 , whereby it can be secured by means of screws upon the projection a^{13} . Said semicylindrical part l^2 also has oppositely-extending lugs or ears l^6 and l^7 , which are provided with holes or perforations l^8 , and 30 directly beneath the lug or ear l^6 there is a curved or cut-away part l^9 . Connected with the said lug or ear l^6 is an upwardly-extending arm l^{10} , which has a longitudinal rib l^{11} on its inner surface, said rib terminating at 35 a point l^{12} on said arm, substantially as illustrated in Fig. 18. At one side of said arm l^{10} there may be a laterally-extending leg l^{13} , having a perforated lug l^{14} for securing it by means of a screw l^{15} to the back a of the casing A . The said receiver or holder section l' 40 also has a semicylindrical part l^{16} and a connecting-wall l^{17} and is provided with oppositely-extending lugs or ears l^{18} and l^{19} , which are provided with holes or perforations l^{20} . 45 Directly beneath the lug or ear l^{19} is a curved cut-away part l^{21} . Connected with the said lug or ear l^{19} is an upwardly-extending arm l^{22} , which has a longitudinal rib or projection l^{23} , terminating at a point l^{24} on said arm, substantially as illustrated in Fig. 19. When 50 the section l has been secured against the back of the casing A , the section l' is placed upon the section l , (with the pump in the socket formed by the two sections,) so that the 55 lugs or ears of the section l' will rest upon the lugs or ears of the section l and the rib l^{23} on the arm l^{22} will rest directly upon the rib l^{11} of the arm l^{10} , the two sections then being firmly secured together by means of screws l^{25} , all of 60 which will be more clearly understood from an inspection of Fig. 8. When secured in this manner, the respective arms l^{10} and l^{22}

will have a suitable space between them and will form a guide for a flanged roller s , connected with a guide-frame u on each pump o . 70 Each air-pump, of which there may be one, two, three, or more, arranged between a corresponding number of pairs of receiving or holding sections, may be of any well-known construction, the pump herein shown consisting, essentially, of a main cylinder o , having a closed bottom o' , an air-outlet o^2 , and a nipple o^3 therein. The upper portion of each pump has an internal screw-thread o^4 , into which is screwed a ring o^5 . Movable arranged 75 in said ring is a cylindrical tube o^6 , having an annular flange o^7 , which normally rests against a packing-ring p at the bottom of said ring o^5 to prevent the withdrawal of said tube o^6 after these parts have been properly assembled. Secured to the bottom o^8 of said tube o^6 , which is also provided with suitable air-passages o^9 , is a cap o^9 and a cup-shaped washer o^{10} , both of the usual form of construction, and between said cap o^9 and the bottom of the cylinder o there is a spring o^{11} . When all the parts have been put together in the manner illustrated in Fig. 12 and the tube o^6 is moved up and down in said cylinder o against the action of the spring therein, a 85 perfectly-operating air-pump is produced and the air can be forced from said cylinder o through the discharge-opening therein into a tube or pipe t .

80 Loosely arranged in the open end of each tube o^6 of the pumps is the guide-frame u , above mentioned. Each frame is provided with a flanged portion u' , which rests directly upon the upper flanged or beaded edge of the said tube o^6 . Said frame u is open, as 85 at u^2 , and rotatively arranged on a pin u^3 , extending across said opening, is a wheel or roller u^4 , which when the pump or pumps have been secured in the casing A is forced into operative rolling contact with the peripheral surface of the cam-disk g by the action of the spring o^{11} in the pump.

In order that the reciprocatory action of the tube o^6 may be properly guided when the machine is in operation and to maintain the proper alinement and operative rolling contact of the roller or rollers u^4 against the cam-surface of the disk g , each guide u has a pair of outwardly-extending and perforated ears or lugs u^5 , between which, on a pin s^2 , I have arranged the flanged rollers s , hereinabove mentioned. Said roller s is in alinement with the roller u^4 , and its flanged portion s' extends between the guide portions of the arms l^{10} and l^{22} , connected with the respective receiver or holder sections l and l' , as more clearly illustrated in Fig. 7. Thus it will be evident from an inspection of Figs. 3, 5, and 7 that after the coin-controlled mechanism has been freed in the manner hereinabove set forth and the shaft c and cam-disk g are being revolved the action of said cam-disk against the rollers or wheels s , connected with the pumps, is such that during each revolu-

tion of the shaft *c* two pumps are constantly forcing compressed air through the tubes or pipes *t*, connected with the respective pumps. As shown in the several views of the drawings, the said tubes or pipes *t* are connected with a suitably-constructed valve-chest *v*, provided with a three-way valve of any well-known construction which has an outlet pipe or tube *v*. Said pipe or tube *v* is connected with a nipple *v*² in the bottom or side of the casing *A*, and connected with said nipple *v*², on the outside of the casing, is a flexible tube or pipe *v*³, which is provided with a suitable mouthpiece *v*⁴, which can be placed over the tire-valve of a bicycle for inflating the latter or over any other valve connected with some other article to be inflated with air.

Although in the present construction of apparatus I have illustrated an arrangement of three air-pumps, it will be clearly evident that I may use but one pump, or I may employ two or more pumps without in the least departing from the scope of my present invention; and, furthermore, I do not wish to be understood as limiting my present invention to the exact arrangements and combinations of the several mechanisms herein set forth nor to the details of the construction thereof, for I am fully aware that they may be departed from without departing from the scope of my present invention.

Having thus described my invention, what I claim is—

1. In a coin-controlled mechanism, a casing, an air pump or pumps in said casing, a coin-chute in said casing, a main shaft, a ratchet-wheel on said main shaft, a projection on said wheel forming a stop, an eccentrically-arranged annular flange on one side of said wheel, a disk *e* in said casing having edge portions *e*¹ and *e*² and diagonally-arranged portions *e*³ and *e*⁴, a connecting means between said eccentric flange and said disk *e* for causing an intermittent rotary motion of said disk, and mechanism, consisting, essentially, of an upwardly-extending arm *h*² normally in locked or holding engagement with the stop on said ratchet-wheel, a downwardly-extending arm *h*³ normally in locked or holding engagement with said disk *e*, and a downwardly-extending arm *h*⁵ projecting beneath the discharge-opening in the coin-chute, to be engaged by a deposited coin, and means connected with the coin-chute to force said coin against the arm *h*⁵ and thereby release the said upwardly-extending arm *h*² from its locked or holding engagement with the ratchet-wheel, and also disengaging said arm *h*³ from the disk *e*, substantially as and for the purposes set forth.

2. In a coin-controlled mechanism, a casing, an air pump or pumps in said casing, a mechanism for operating said pump or pumps, a coin-chute in said casing, a main shaft, a ratchet-wheel on said shaft, a projection on said wheel forming a stop, an eccentrically-arranged annular flange on one side of said

wheel, a disk *e* in said casing having edge portions *e*¹ and *e*² and diagonally-arranged portions *e*³ and *e*⁴, a ratchet-disk *e*⁶ connected with said disk *e*, a lever or rod *k*, a pawl or dog pivoted to said lever or arm and in engagement with said ratchet-disk, a roller or wheel on the opposite end of said lever or rod *k* in rolling contact with the eccentric flange *h*² on said ratchet-wheel on the main shaft, and mechanism, consisting, essentially, of an upwardly-extending arm *h*² normally in locked or holding engagement with the stop on said ratchet-wheel, a downwardly-extending arm *h*³ normally in locked or holding engagement with said disk *e*, and a downwardly-extending arm *h*⁵ projecting beneath the discharge-opening in the coin-chute, to be engaged by a deposited coin, and means connected with the coin-chute to force said coin against the arm *h*⁵ and thereby release said upwardly-extending arm *h*² from its locked or holding engagement with the ratchet-wheel, and also disengaging said arm *h*³ from the disk *e*, substantially as and for the purposes set forth.

3. In a coin-controlled mechanism, a casing, an air pump or pumps, comprising a cylinder and a spring-actuated and reciprocatory-moving tube in said cylinder, forming the piston of the pump, a main shaft in said casing, a cam-disk on said shaft for actuating said pump-tube, a coin-chute in said casing, a ratchet-wheel on said main shaft, said wheel having a projection forming a stop, and mechanism, normally in locked or holding engagement with the stop on said ratchet-wheel, arranged to be freed by a deposited coin and permit the operation of said ratchet-wheel and the pump operating mechanism, substantially as and for the purposes set forth.

4. In a coin-controlled mechanism, a casing, an air pump or pumps, comprising a cylinder and a spring-actuated and reciprocatory-moving tube in said cylinder, forming the piston of the pump, a main shaft in said casing, a cam-disk on said shaft for actuating said pump-tube, a coin-chute in said casing, a ratchet-wheel on said shaft, said wheel having a projection forming a stop, and mechanism, consisting, essentially, of an upwardly-extending arm normally in locked or holding engagement with the stop on said ratchet-wheel, and a downwardly-extending arm projecting beneath the discharge-opening in the coin-chute, to be engaged by a deposited coin, and means connected with the coin-chute to force said coin against the said downwardly-projecting arm and thereby release the said upwardly-extending arm from its locked or holding engagement with the ratchet-wheel, substantially as and for the purposes set forth.

5. In a coin-controlled mechanism, a casing, an air pump or pumps, comprising a cylinder and a spring-actuated and reciprocatory-moving tube in said cylinder, forming the piston of the pump, a main shaft in said casing, a cam-disk on said shaft for actuating said pump-tube, a coin-chute in said casing, a ratchet-

- wheel on said main shaft, a projection on said wheel forming a stop, an eccentrically-arranged annular flange on one side of said wheel, a disk e in said casing having edge portions e' and e^2 and diagonally-arranged portions e^3 and e^4 , a connecting means between said eccentric flange and said disk e for causing an intermittent rotary motion of said disk, and mechanism, consisting, essentially, 5 of an upwardly-extending arm h^2 normally in locked or holding engagement with the stop on said ratchet-wheel, a downwardly-extending arm h^3 normally in locked or holding engagement with said disk e , and a downwardly-extending arm h^5 projecting beneath the discharge-opening in the coin-chute, to be engaged by a deposited coin, and means connected with the coin-chute to force said coin against the arm h^5 and thereby release the said 10 upwardly-extending arm h^2 from its locked or holding engagement with the ratchet-wheel, and also disengaging said arm h^3 from the disk e , substantially as and for the purposes set forth.
- 15 6. In a coin-controlled mechanism, a casing, an air pump or pumps, comprising a cylinder and a spring-actuated and reciprocatory-moving tube in said cylinder, forming the piston of the pump, a main shaft in said casing, a cam-disk on said shaft for actuating said pump-tube, a coin-chute in said casing, a ratchet-wheel on said shaft, a projection on said wheel forming a stop, an eccentrically-arranged flange on one side of said wheel, a disk e in said casing having edge portions e' and e^2 and diagonally-arranged portions e^3 and e^4 , a ratchet-disk e^6 connected with said disk e , a lever or rod k , a pawl or dog pivoted to said lever or rod and in engagement with said ratchet-disk, a roller or wheel on the opposite end of said lever or rod k in rolling contact with the eccentric flange on said ratchet-wheel on the main shaft, and mechanism, consisting, essentially, of an upwardly-extending arm h^2 20 normally in locked or holding engagement with the stop on said ratchet-wheel, a downwardly-extending arm h^3 normally in locked or holding engagement with said disk e , and a downwardly-extending arm h^5 projecting beneath the discharge-opening in the coin-chute, to be 25 engaged by a deposited coin, and means connected with the coin-chute to force said coin against the arm h^5 and thereby release said upwardly-extending arm h^2 from its locked or holding engagement with the ratchet-wheel, and also disengaging said arm h^3 from the disk e , substantially as and for the purposes set forth.
- 30 7. In a coin-controlled mechanism, a casing, a main shaft and a coin-chute in said casing, a ratchet-wheel on said main shaft, a projection on said wheel forming a stop, an eccentrically-arranged annular flange on one side of said wheel, a disk e in said casing having edge portions e' and e^2 and diagonally-arranged portions e^3 and e^4 , a connecting means 35 between said eccentric flange and said disk e for causing an intermittent rotary motion of said disk, and mechanism, consisting, essentially, of an upwardly-extending arm h^2 normally in locked or holding engagement with the stop on said ratchet-wheel, a downwardly-extending arm h^3 normally in locked or holding engagement with said disk e , and a downwardly-extending arm h^5 projecting beneath the discharge-opening in the coin-chute, to be 40 engaged by a deposited coin, and means connected with the coin-chute to force said coin against the arm h^5 and thereby release said upwardly-extending arm h^2 from its locked or holding engagement with the ratchet-wheel, and also disengaging said arm h^3 from the disk e , substantially as and for the purposes set forth.
- 45 8. In a coin-controlled mechanism, a casing, a main shaft and a coin-chute in said casing, a ratchet-wheel on said main shaft, a projection on said wheel forming a stop, an eccentrically-arranged annular flange on one side of said wheel, a disk e in said casing having edge portions e' and e^2 and diagonally-arranged portions e^3 and e^4 , a connecting means 50 between said eccentric flange and said disk e for causing an intermittent rotary motion of said disk, and mechanism, consisting, essentially, of an upwardly-extending arm h^2 normally in locked or holding engagement with the stop on said ratchet-wheel, a downwardly-extending arm h^3 normally in locked or holding engagement with said disk e , and a downwardly-extending arm h^5 projecting beneath the discharge-opening in the coin-chute, to be 55 engaged by a deposited coin, and means connected with the coin-chute to force said coin against the arm h^5 and thereby release said upwardly-extending arm h^2 from its locked or holding engagement with the ratchet-wheel, and also disengaging said arm h^3 from the disk e , substantially as and for the purposes set forth.
- 60 9. In a coin-controlled mechanism, the combination, with a main-shaft-operating mechanism, of a pump, comprising a cylinder and a reciprocatory-moving tube acting as a piston in said cylinder, a guide-frame in the open end of said tube, a roller or wheel in said guide-frame, a cam-disk on said main shaft with which said roller or wheel is in operative rolling contact, a coin-chute, a ratchet-wheel on said main shaft, said wheel having a projection forming a stop, and mechanism normally in locked or holding engagement 65 with the stop on said ratchet-wheel, arranged to be freed by a deposited coin and permit the operation of said ratchet-wheel and pump-operating cam-disk, substantially as and for the purposes set forth.
- 65 10. In a coin-controlled mechanism, the combination, with a main-shaft-operating mechanism, of a pump, comprising a cylinder and a reciprocatory-moving tube acting as a pis-

for causing an intermittent rotary motion of said disk, and mechanism, consisting, essentially, of an upwardly-extending arm h^2 normally in locked or holding engagement with the stop on said ratchet-wheel, a downwardly-extending arm h^3 normally in locked or holding engagement with said disk e , and a downwardly-projecting arm h^5 projecting beneath the discharge-opening in the coin-chute, to be engaged by a deposited coin, and means connected with the coin-chute to force said coin against the arm h^5 and thereby release the said upwardly-extending arm h^2 from its locked or holding engagement with the ratchet-wheel, and also disengaging said arm h^3 from the disk e , substantially as and for the purposes set forth. 70

75 8. In a coin-controlled mechanism, a casing, a main shaft and a coin-chute in said casing, a ratchet-wheel on said shaft, a projection on said wheel forming a stop, an eccentrically-arranged annular flange on one side of said wheel, a disk e in said casing having edge portions e' and e^2 and diagonally-arranged portions e^3 and e^4 , a connecting means 80 between said eccentric flange and said disk e for causing an intermittent rotary motion of said disk, and mechanism, consisting, essentially, of an upwardly-extending arm h^2 normally in locked or holding engagement with the stop on said ratchet-wheel, a downwardly-extending arm h^3 normally in locked or holding engagement with said disk e , and a downwardly-extending arm h^5 projecting beneath the discharge-opening in the coin-chute, to be 85 engaged by a deposited coin, and means connected with the coin-chute to force said coin against the arm h^5 and thereby release the said upwardly-extending arm h^2 from its locked or holding engagement with the ratchet-wheel, and also disengaging said arm h^3 from the disk e , substantially as and for the purposes set forth. 90

90 9. In a coin-controlled mechanism, the combination, with a main-shaft-operating mechanism, of a pump, comprising a cylinder and a reciprocatory-moving tube acting as a piston in said cylinder, a guide-frame in the open end of said tube, a roller or wheel in said guide-frame, a cam-disk on said main shaft with which said roller or wheel is in operative rolling contact, a coin-chute, a ratchet-wheel on said main shaft, said wheel having a projection forming a stop, and mechanism normally in locked or holding engagement 95 with the stop on said ratchet-wheel, arranged to be freed by a deposited coin and permit the operation of said ratchet-wheel and pump-operating cam-disk, substantially as and for the purposes set forth. 100

95 10. In a coin-controlled mechanism, the combination, with a main-shaft-operating mechanism, of a pump, comprising a cylinder and a reciprocatory-moving tube acting as a pis- 105

110 11. In a coin-controlled mechanism, the combination, with a main-shaft-operating mechanism, of a pump, comprising a cylinder and a reciprocatory-moving tube acting as a piston in said cylinder, a guide-frame in the open end of said tube, a roller or wheel in said guide-frame, a cam-disk on said main shaft with which said roller or wheel is in operative rolling contact, a coin-chute, a ratchet-wheel on said main shaft, said wheel having a projection forming a stop, and mechanism normally in locked or holding engagement 115 with the stop on said ratchet-wheel, arranged to be freed by a deposited coin and permit the operation of said ratchet-wheel and pump-operating cam-disk, substantially as and for the purposes set forth. 120

115 12. In a coin-controlled mechanism, the combination, with a main-shaft-operating mechanism, of a pump, comprising a cylinder and a reciprocatory-moving tube acting as a piston in said cylinder, a guide-frame in the open end of said tube, a roller or wheel in said guide-frame, a cam-disk on said main shaft with which said roller or wheel is in operative rolling contact, a coin-chute, a ratchet-wheel on said main shaft, said wheel having a projection forming a stop, and mechanism normally in locked or holding engagement 125 with the stop on said ratchet-wheel, arranged to be freed by a deposited coin and permit the operation of said ratchet-wheel and pump-operating cam-disk, substantially as and for the purposes set forth. 130

ton in said cylinder, a guide-frame in the open end of said tube, a roller or wheel in said guide-frame, a cam-disk on said main shaft with which said roller or wheel is in operative rolling contact, a coin-chute, a ratchet-wheel on said main shaft, said wheel having a projection forming a stop, and mechanism, consisting, essentially, of an upwardly-extending arm normally in locked or holding engagement with the stop on said ratchet-wheel, and a downwardly-extending arm projecting beneath the discharge-opening in the coin-chute, to be engaged by a deposited coin, and means connected with the coin-chute to force said coin against the said downwardly-projecting arm and thereby release the said upwardly-extending arm from its locked or holding engagement with the ratchet-wheel, substantially as and for the purposes set forth.

11. In a coin-controlled mechanism, the combination, with a main-shaft-operating mechanism, of a pump, comprising a cylinder and a reciprocating-moving tube acting as a piston in said cylinder, a guide-frame in the open end of said tube, a roller or wheel in said guide-frame, a cam-disk on said main shaft with which said roller or wheel is in operative rolling contact, a ratchet-wheel on said main shaft, a projection on said wheel forming a stop, an eccentrically-arranged annular flange on one side of said wheel, a disk *e* in said casing having edge portions *e'* and *e''* and diagonally-arranged portions *e³* and *e⁴*, a connecting means between said eccentric flange and said disk *e* for causing an intermittent rotary motion of said disk, and mechanism, consisting, essentially, of an upwardly-extending arm *h²* normally in locked or holding engagement with the stop on said ratchet-wheel, a downwardly-extending arm *h³* normally in locked or holding engagement with said disk *e*, and a downwardly-extending arm *h⁵* projecting beneath the discharge-opening in the coin-chute, to be engaged by a deposited coin, and means connected with the coin-chute to force said coin against the arm *h⁵* and thereby release said upwardly-extending arm *h²* from its locked or holding engagement with the ratchet-wheel, and also disengaging said arm *h³* from the disk *e*, substantially as and for the purposes set forth.

12. In a coin-controlled mechanism, the combination, with a main-shaft-operating mechanism, of a pump, comprising a cylinder and a reciprocating-moving tube acting as a piston in said cylinder, a guide-frame in the open end of said tube, a roller or wheel in said guide-frame, a cam-disk on said main shaft with which said roller or wheel is in operative rolling contact, a ratchet-wheel on said main shaft, a projection on said wheel forming a stop, an eccentrically-arranged annular flange on one side of said wheel, a disk *e* in said casing having edge portions *e'* and *e''* and diagonally-arranged portions *e³* and *e⁴*, a ratchet-disk *e⁶* connected with said disk *e*, a lever or rod *k*, a pawl or dog pivoted to said lever or rod and in engagement with said ratchet-disk, a roller or wheel on the opposite end of said lever or rod *k* in rolling contact with the eccentric flange on said ratchet-wheel on the main shaft, and mechanism, consisting, essentially, of an upwardly-extending arm *h²* normally in locked or holding engagement with the stop on said ratchet-wheel, a downwardly-extending arm *h³* normally in holding or locked engagement with said disk *e*, and a downwardly-extending arm *h⁵* projecting beneath the discharge-opening in the coin-chute, to be engaged by a deposited coin, and means connected with the coin-chute to force said coin against the arm *h⁵* and thereby release said upwardly-extending arm *h²* from its locked or holding engagement with the ratchet-wheel, and also disengage said arm *h³* from the disk *e*, and a connecting-spring *m* between said rod or lever

k and the said arm *h*³, substantially as and for the purposes set forth.

15. In a coin-controlled mechanism, a casing, an air pump or pumps, comprising a cylinder and spring-actuated and reciprocatory-moving tube in said cylinder, forming the piston of the pump, a main shaft in said casing, a cam-disk on said shaft for actuating said pump-tube, a coin-chute in said casing, 5 a ratchet-wheel on said shaft, a projection on said wheel forming a stop, an eccentrically-arranged flange on one side of said wheel, a disk *e* in said casing having edge portions *e*¹ and *e*² and diagonally-arranged portions *e*³ and *e*⁴, a 10 ratchet-disk *e*⁶ connected with said disk *e*, a lever or rod *k*, a pawl or dog pivoted to said lever or rod and in engagement with said ratchet-disk, a roller or wheel on the opposite end of said lever or rod *k* in rolling contact 15 with the eccentric flange on said ratchet-wheel on the main shaft, and mechanism, consisting, essentially, of an upwardly-extending arm *h*² normally in locked or holding

engagement with the stop on said ratchet-wheel, a downwardly-extending arm *h*³ normally in locked or holding engagement with said disk *e*, and a downwardly-extending arm *h*⁵ projecting beneath the discharge-opening in the coin-chute, to be engaged by a deposited coin, and means connected with the coin-chute to force said coin against the arm *h*⁵ and thereby release said upwardly-extending arm *h*² from its locked or holding engagement with the ratchet-wheel, and also disengaging said arm *h*³ from the disk *e*, and a connecting-spring *m* between said rod or lever *k* and said arm *h*³, substantially as and for the purposes set forth. 25 30 35

In testimony that I claim the invention set forth above I have hereunto set my hand this 27th day of June, 1898.

CLEMENT C. CLAWSON.
